Primary Examiner — Prabhakar G Deshmukh(74) *Attorney, Agent, or Firm* — Thomas M. Freiburger(57) **CLAIM**

The ornamental design for an electronic locker lock, substantially as shown and described.

DESCRIPTION

FIG. 1 is a front left perspective view of a first embodiment of an electronic locker lock according to my new design; FIG. 2 is a top plan view thereof;

FIG. 3 is a rear elevation view thereof;

FIG. 4 is a left side view thereof;

FIG. 5 is a front elevation view thereof;

FIG. 6 is a right side view thereof;

FIG. 7 is a bottom plan view thereof;

FIG. 8 is a front left perspective view of a second embodiment of an electronic locker lock according to my new design;

FIG. 9 is a top plan view thereof;

FIG. 10 is a rear elevation view thereof;

FIG. 11 is a left side view thereof;

FIG. 12 is a front elevation view thereof;

FIG. 13 is a right side view thereof; and,

FIG. 14 is a bottom plan view thereof.

Features shown in dashed lines are not part of the claimed design.

1 Claim, 2 Drawing Sheets(56)
